(57) **CLAIM**

The ornamental design for an ornament, as shown and described.

DESCRIPTION

FIG. 1 is a perspective view of an ornament in accordance with the present design;

FIG. 2 is a right side elevational view thereof;

FIG. 3 is a left side elevational view thereof;

FIG. 4 is a front side elevational view thereof;

FIG. 5 is a rear elevational view thereof;

FIG. 6 is a top plan view thereof; and,

FIG. 7 is a bottom view thereof.

The surface shading is intended to illustrate contrast in the design.
